UNITED STATES PATENT OFFICE.

JAMES G. NOLEN, OF CHICAGO, ILLINOIS, ASSIGNOR, BY MESNE ASSIGNMENTS, TO AUTOMATIC FIRE PROTECTION COMPANY, A CORPORATION OF MAINE.

FIRE-PROTECTION SYSTEM.

No. 828,046.

Specification of Letters Patent.

Patented Aug. 7, 1906.

Application filed September 6, 1904. Serial No. 223,534.

To all whom it may concern:

Be it known that I, JAMES G. NOLEN, of Chicago, in the county of Cook and State of Illinois, have invented certain new and useful Improvements in Fire-Protection Systems; and I hereby declare that the following is a full, clear, and exact description thereof, reference being had to the accompanying drawings, which form part of this specification.

My invention relates to improvements in fire-protection systems wherein are employed automatic sprinkler devices adapted to be automatically set in operation upon the occurrence of fire and with which are associated signaling devices for indicating conditions in the extinguishing system.

In automatic fire-extinguishing systems it is important to know when water is in motion through the system; and one of the salient objects of my invention is to provide in conjunction with parts of a fire-extinguisher system means for indicating the commencement of water-flow through the piping of the system.

A further object of my invention is to provide a movable part in a fire-extinguisher system which will be sensitive to even slight movement of the water and will be capable of actuating a signaling device associated therewith.

A further object of my invention is to provide a connection between such moving part and a normally wound signal-transmitting instrumentality so constructed and associated with the extinguisher part that the said instrumentality is not actuated to send a full alarm should the water-flow be of momentary duration only.

With a view to attaining these and further objects, which will become apparent to those skilled in the art from the following description, my invention consists in the features of construction and arrangement and combinations of parts hereinafter fully pointed out, and specified in the claims.

Referring now to the drawings, Figure 1 is a view partially in elevation, partially in section, and partially diagrammatic, showing one operative embodiment of my invention. Fig. 2 is a detail section taken on line 2 2 of Fig. 1. Fig. 3 is a similar view to Fig. 1,

showing another embodiment of my invention.

Throughout the drawings like numerals of reference refer always to like parts.

Referring now to said drawings, and particularly to Fig. 1 thereof, A represents a riser or other pipe of an automatic sprinkler system provided with a check or other automatic valve B.

C indicates a by-pass pipe around the riser-valve B, and D indicates a small check-valve in the by-path C, having a movable part or valve-head d, preferably of the flap variety.

d' represents the stem of the movable valve member d, connected to move therewith, and d² represents a lever-arm fixedly connected to the stem d'.

The provision of the small automatic valve in the by-pass is for the purpose, among others, of obtaining sensibility to small current-flow, for it is well known that a check-valve in the main pipe or riser, such as the valve B, scarcely responds at all to a small flow of water, such as that caused by the breaking of a single sprinkler-head or a relatively small leak. The check-valve d being very light, however, is quite sensitive and will respond quickly and positively to a slight flow occasioned by some such causes as those described. Further, it will be apparent that the valve-head d will respond more quickly to sudden impulses than the valve B on account of its lighter weight.

I associate with the automatic by-pass valve d a normally wound alarm-box of the signal-transmitting mechanism and so connect the said transmitting mechanism with the movable valve-head that the maintenance of said head in open position for a prolonged time causes the said transmitting mechanism to transmit to a central station a predetermined alarm, but so that the temporary opening of the valve does not result in the transmission of such alarm.

Referring now particularly to Fig. 1, E represents a normally wound signal-transmitting mechanism, preferably of the well-known messenger-call type, but which may as to its general features be of any suitable operative construction. The box E is preferably adapted when its mechanism is free

from restraint to transmit its characteristic number a plurality of times.

5 *e* represents a rotating part driven by the box motor mechanism so as to make one revolution for each round of signals sent by the box. The rotating part *e* is provided with a notch *e'* for a purpose to be described.

10 *e²* indicates an escapement-wheel which may be in any way conveniently driven by the train, and *e³* its associated pallet.

15 *e⁴* indicates a stem rigidly connected with the pallet to be vibrated as the latter moves during the operation of the transmitter, said stem at its end having a transversely-bent portion *e⁵*.

20 *F* indicates a signal-recording device preferably arranged at the central station, and *G* a source of current-supply therefor connected in a circuit *H*, including the signal-responsive device *F* and the signal-transmitter *E*. A controlling device for the signal-transmitter *E* is provided and associated for operation with the automatic valve-head *d*, said controlling device being so arranged relative to 25 the valve that when the valve-head is lifted and maintained in raised position by the flow of the water the controlling device is thereby coincidentally maintained in inactive position for releasing the transmitting device to 30 send in its full number of rounds for which it is set, but so that when the valve is opened and then promptly reseated, as by a temporary rush of water, the controlling device is actuated to permit its signaling device to 35 send only a single round and then stop said signal device.

35 In the specific construction shown, 5 indicates a lever pivoted, as at 6, on any suitable support provided at one extremity with an 40 inturned end 7; adapted to engage in the recess *e'* of the rotating part *e* of the signal-box.

45 8 indicates an arm extending at right angles to the arm 5 and having its extremity overlying the lever-arm *d*, associated with the valve *D*. The arm 8 is provided with a depending stud 9, which when the said arm is depressed lies in the path of vibration of the end *e⁵* of the vibrating stem *e⁴* of the signal-box, as shown in Fig. 2, but which when 50 elevated to such an extent as to permit the finger 7 of the controlling device to escape the notch *e'* to free the said stem for vibration.

55 A suitable spring *s* is provided tending to maintain the controlling device in operative position.

60 The operation of this specific construction is as follows: As soon as the movable valve member *d* is lifted by the commencement of water-flow through the by-pass *C* it elevates the arm 8 against the tension of its spring *s*, freeing the pallet-stem *e⁴* and withdrawing the finger 7 from its notch *e'* in the rotating part *e*. Consequently the signal-transmitter 65 is started in motion to send the signal to the

responsive device *F* at the central station. As long as the valve member *d* remains in raised position under the influence of the moving water body the controlling device is maintained in its inoperative position; but if 70 said valve *d* returns to its seat the controlling device tends to return to its original position under the influence of its spring. It will be noted, however, that after the arm 7 is once moved from its notch *e'* it travels upon the 75 peripheral surface of the rotating part *e*, and therefore the lug 9 upon the arm 8 cannot stop the vibration of the pallet until the finger 7 again drops into its notch *e'* in the rotating part of the signal-box. As soon, however, as the round which the box may then be sending is completed the controlling device restores itself to initial position to stop the box. It will be apparent now that if the water-flow be prolonged the controlling device 80 will be maintained in releasing position and the signal-transmitter permitted to send its complete signal to the central station, indicating that attention is required to the system. If, on the other hand, said valve opens 85 only momentarily in response to a "kick" or sudden vibration in the water-pressure, the signal-box is actuated to send only a single round, and while the central station is notified of the opening of the valve it becomes 90 apparent at the station that the valve has again closed itself, for the reason that only the short signal is received. It may be understood at the central station that a signal of 95 two or more rounds of the box requires attention, in which case if the box be wound to send four or five rounds when entirely free from restraint the occurrence of several impulses in the pipe, each actuating the box to 100 send one round, does not incapacitate said 100 box for later transmitting a signal which will demand the attention of the central observer.

105 In Fig. 3 I have shown another embodiment of my invention. In said figure the alarm-box *E* and its association with a signaling-circuit identical with the arrangement shown in Fig. 1 and the controlling mechanism of the box works on the same principle; but its connection with the valve *D* is different.

110 Referring to the specific construction of the controller shown in Fig. 3, 5 indicates an arm pivoted at 6 and provided with a hook 7, cooperating with the rotating element *e*, as in the device above described, and 8' indicates the trip-arm provided with the detent arrangement 9, cooperating with the end *e⁵* of the vibrating pallet-stem *e⁴*, and thence bent downward and provided with an inturned end portion 8'', arranged in front of the pivot 115 6. 10 indicates generally a mechanical timing device, comprising, essentially, a frame member 11, pivoted, as at 12, preferably below its center of gravity, so that it is not in stable equilibrium, and provided at its lower 120

130

end with an arm 13, which overlies the end of the lever-arm d^2 , connected with the valve.

Mounted in the frame of the controlling device is a dumb-bell-shaped member 14, having chambers 15 and 16 at its opposite ends, connected by a restricted passage 17. Within this hollow member is arranged a body 18 of heavy liquid, such as mercury, adapted when the device is tilted from one side to the other to flow from one chamber to the other through the restricted passage in a predetermined time. The device is so arranged that when in normal position a preponderance of the weight rests on the side thereof, which tends to hold the arm 13 in contact with the lever-arm d^2 ; but if said device be tipped from its normal position by the raising of the arm d^2 for a sufficient length of time the mercury will flow through the restricted passage into the chamber 16, changing the preponderating weight to that side and causing the frame to fall on its now preponderating side. An arm 19 is provided on the normally elevated side of the frame and so disposed that when the frame 11 is tilted by the elevation of the valve-arm d^2 said arm 19 contacts with or stands slightly above the inturned end 8" of the controlling mechanism without moving the latter. It will be apparent now that if the valve d be raised and immediately returned to its seat in consequence of a kick in the water-pressure the frame 11 is tilted momentarily; but the restricted connection between the chambers is so small that sufficient mercury cannot flow therethrough in a short time to change the preponderance of weight from its normal side to the other, and consequently when the valve returns to normal position the movable frame also returns to its normal position without having disturbed the controlling device of the signal-transmitter. If, however, the valve be raised and maintained in raised position, the timing device is maintained with its heavier end elevated until sufficient mercury flows through the restricted passage to throw the preponderating weight upon the side of the chamber 16, whereupon the frame 11 tilts still farther to the position indicated in dotted lines in Fig. 3 and pulls down the controlling-lever 5, thereby tripping the box. It will be apparent that when the box is thus tripped it sends its full signal, no signal at all being sent when the mere momentary opening of the valve occurs.

While I have herein described in some detail two operative embodiments of my invention, I do not desire to be understood as limiting myself to the specific construction of either further than as claimed or as limiting the changes which may be made within the scope of my invention to such changes as are illustrated in the different embodiments, the modification being shown merely for the purpose of indicating different embodiments of

my invention which may conveniently be used. I do, however, limit my present invention as to the timing arrangement to a timing means mechanically connected with the transmitter to control the latter, the broader idea of any character of connection being made the subject of claims in my co-pending application, Serial No. 224,925, filed September 17, 1904.

Having thus described my invention, what I claim, and desire to secure by Letters Patent of the United States, is—

1. The combination with a main pipe and a valve therein of a by-pass around said main valve, a part in said by-pass movable from normal position when water flows through said by-pass and to normal position on the cessation of water-flow, a signal system comprising a suitable circuit, a signal-responsive device, a source of current-supply, and a normally wound signal-transmitter adapted when maintained in condition for operation to transmit a plurality of separate signals, and when conditioned for inactivity to stop upon the completion of the signal then being transmitted, and operative connection between the part in the by-pass and the transmitter whereby movement of said part from normal position conditions the transmitter for operation, and return of said part to normal position conditions said transmitter for inactivity.

2. The combination with a main pipe and a valve therein, of a by-pass around said valve, a lighter automatic valve in said by-pass, a signal system comprising a suitable circuit, a source of current-supply, a signal-responsive device, and a normally wound signal transmitter having an escapement, and adapted when maintained in condition for operation to transmit a plurality of separate signals, a controlling device for said transmitter comprising a stem projecting from an escapement member, a part coacting with said stem to prevent its vibration when said part is in one position, and to permit its vibration when the part is in another position, and means carried by the transmitting mechanism for timing the return of said part to normal position after movement therefrom, and an operative connection between the by-pass valve and said controlling part whereby the opening of said by-pass valve moves said controlling part from normal position to condition the signal-transmitter for operation.

3. In combination a signal-transmitter, a movable signal-initiator to be supervised, a timing device operatively associated with the transmitter and signal-initiator, and arranged, when maintained in functionally operative condition by the initiator for a predetermined time, to mechanically condition the transmitter for operation, and when maintained in such condition for less than

the predetermined time to restore itself to normal condition without affecting the transmitter.

4. In combination a valve, a signal-transmitter and a timing device, responsive to an abnormal condition of the valve for a definite time to mechanically trip the transmitter and self-restoring after maintenance of such abnormal condition for less than such definite time.

5. In combination with a valve, a normally wound signal device, and means for mechanically tripping the signal device comprising a movable part associated with the 15 valve for movement thereby, and a mechanical timing device arranged to be moved from normal position by said movable part and, when maintained in abnormal position for a predetermined time, to mechanically trip the 20 signal device, said timing device being self-restored to normal condition after mainte-

nance in abnormal position for less than the predetermined time.

6. In combination with a device to be supervised, a normally wound signal device, a 25 timing device mechanically connected with the signal device to control the signal device and controlled by the device to be supervised, said timing device being adapted to condition the signal device for operation only after 30 its maintenance in condition for operation by the device to be supervised for a predetermined time and to restore itself to initial condition after maintenance in timing condition for less than the predetermined time. 35

In testimony that I claim the foregoing as my own I affix my signature in presence of two witnesses.
